UNITED STATES PATENT OFFICE

ALFRED H. GRUPPE, OF MILWAUKEE, WISCONSIN, ASSIGNOR OF ONE-HALF TO
THOMAS L. DUROCHER, OF DETOUR, MICHIGAN

CRIB, CAISSON, AND THE LIKE

Application filed July 6, 1929. Serial No. 376,363.

The invention relates to certain improvements in metallic supporting structures, such as cribs, caissons, coffer-dams, retaining walls and the like, and has for its object to provide a structure of the character indicated comprising wall sections in the form of panels built up of channel irons with their marginal flanges in parallel, faced, abutting relation, the vertical edges of adjacent panels being united by continuous connecting members, preferably in the form of sections of sheet piling riveted to the edges, so that the individual wall sections may be fabricated under most advantageous conditions and transported to the site upon which the structure is to be erected, where the several wall sections may be quickly assembled and connected together to form an enclosure or a complete wall construction of the desired shape and size. The invention is illustrated in the accompanying drawings, in which:—

Fig. 1 is a plan view of a crib, caisson or foundation structure.

Fig. 2 is an elevation thereof.

Fig. 3 is an enlarged fragmentary plan view showing one form of joint between the wall sections.

Fig. 4 is an elevation thereof.

Fig. 5 is a view similar to Fig. 3, illustrating a modification of the jointure.

Fig. 6 is an elevation thereof.

Fig. 7 is a plan view of a further modification showing a structure formed of generally prismatic units.

Fig. 8 is a fragmentary plan view showing the joint between adjacent sections.

Fig. 9 is a perspective view of one of the half sections of interlocking sheet piling employed in forming the joints.

Fig. 10 is a plan view of a further modification, illustrating the construction as applied to generally rectangular structures.

Fig. 11 is a fragmentary elevation thereof.

Fig. 12 is a fragmentary plan view of two adjacent wall sections with vertical plates connecting the adjacent edges of the sections.

Referring to Figs. 1 to 4 of the drawings, the exemplary structure is in the form of a crib, caisson or foundation involving separate panel-like wall units, each unit being

made up of a series of abutted channel beams 1 cut to proper length with their flanges in parallel abutting relation and properly connected by rivets, welding or other suitable means. Preferably, each wall section is formed of two spaced parallel panels formed by a series of superposed channel irons 1 and 1' in the relation specified, the respective panels being cross connected by suitable braces 2.

As indicated, each wall section is built up as a separate unit, so that, when the several sections are transported to the place of erection, they may be readily placed in position and joined together to form the complete structure. To facilitate the proper jointure of the several wall sections, in the particular form of the invention illustrated in the figures aforesaid, there is secured to the vertical marginal edge of each panel a half section of standard sheet piling 3 or 3', which are adapted to be interengaged by a whole section of sheet piling 4, 4', which may be driven vertically into position, after the adjacent wall sections have been properly located. When all of the sections have been thus assembled and joined by the sections of sheet piling, the structure will be united into a rigid substantially water-tight whole to receive the filling of concrete, rubble or other material, if such is to be used, and to constitute a firm and lasting foundation for any superstructure that is to be erected thereon.

Under certain conditions, it may be found advantageous to simplify the joint between adjacent wall sections, in which case half sections only of the sheet piling will be employed in the relation shown in Figs. 5 and 6, in which the half sections of sheet piling 3 and 3' are secured, by riveting or otherwise, to the vertical marginal edges of the respective panels 1 and 1', so that the several wall sections may be assembled and connected by lowering each section into position, so that the interlocking members of the sheet piling will be engaged in the manner and form illustrated more particularly in Fig. 5.

It will be understood that, when necessary, cross braces may be applied between adjacent wall sections or between opposite wall

sections for further strengthening the structure as a whole.

Conditions may arise in which it may be necessary to provide the structure as a whole with additional strength to support heavy loads and to resist lateral stresses, in which case the individual wall units may be given the form illustrated in Figs. 7 and 8, in which the peripheral wall sections are formed of parallel spaced panels built up of separate channel sections 10 and 10' with their flanges in faced abutting relation, as hereinbefore described, with angularly disposed panels formed of similar channels 11 and 12 connected to the peripheral panels by vertical angle irons 13 and 14, which angular panels are connected at their point of jointure by vertical angles 15, or other structural shapes. By this structural arrangement, it will be seen that each wall section is in the form of a hollow prismatic unit having a double peripheral wall and single lateral walls, all formed of abutted channels. In this case, as in that illustrated in the preceding figures, the jointure of the several adjacent wall units or structures may be made by interlocking sections of sheet piling, which, however, may be applied to the vertical marginal edges only of the outer panels. If desired, each joint may consist of two half sections 3, 3' of sheet piling riveted or otherwise secured to the vertical edges of the front panels, which half sections are connected by a whole section 4, as in Fig. 1, or, if conditions permit, the particular form of joint shown in Fig. 5 may be employed.

The invention is also applicable to the erection of substantially straight walls, foundations, piers or the like, in which case the arrangement shown in Figs. 10 and 11 may be employed, which illustrates separate longitudinal panel sections built up of abutted channels 20 with cross panels 20' similarly constructed and connected to the panels 20 by angles 21, with the adjacent ends of the longitudinal panels 20 connected by the sheet piling sections 3, 3' and 4.

Certain conditions may arise in which the joints between the panels constituting elements of the walls of the structure, may be made in the form of vertical plates 30 and 30' riveted to the edges of adjacent panels, as illustrated in Fig. 12. In this case, the several wall sections will be fabricated in mills adapted for this type of work, the marginal edges of each of the panels being provided with spaced rivet holes, the jointure plates 30 and 30' being cut to proper length and width and provided with rivet holes registering with those in the edges of the panels, so that, when the preformed wall sections have been properly assembled in the place of erection, the plates 30, 30' may be dropped into position and readily secured by rivets or equivalent fastening means to rigidly connect

the vertical edges of adjacent panels, or a plate 30 or 30' may be attached to one edge of a panel, after the latter has been made up at the mill or factory, so that each unit will consist of a panel and one jointure plate, thereby reducing by one-half the amount of riveting to be done at the site where the structure is to be erected.

While the invention has been conventionally illustrated as involving channel irons or beams disposed in horizontal relation with their flanges parallel and abutting, it will be understood that the panels may be fabricated of similar channels arranged vertically and abutted flange to flange in parallel series and in sufficient number to form the panel or wall section of the desired width.

It is also to be observed that, in using the full sheet piling sections interposed between the half sections attached to the vertical marginal edges of adjacent panels, the intermediate whole sheet piling sections may be driven below the bottom of the structure and into the bed of the waterway or other location to solid footings and thereby afford an effective anchorage and an element of added strength to the completed structure.

What I claim is:

1. A metal structure for cribs, caissons and the like, comprising wall panels of channel beams in abutted parallel relation united flange to flange, and sheet piling sections secured to and uniting the vertical edges of adjacent panels.

2. A metal structure for cribs, caissons and the like, comprising wall sections of parallel spaced panels of channel beams in abutted parallel relation united flange to flange, cross bracing between the parallel panels, and sheet piling sections secured to and connecting the vertical edges of adjacent panels.

3. A unit wall structure for cribs, caissons and the like, comprising parallel spaced panels each formed of channel beams with their flanges in parallel abutting relation, cross bracing between the panels, and a sheet piling section secured to each vertical edge of said panels.

4. A unit wall structure for cribs, caissons and the like, comprising a panel formed of channel beams with their flanges in parallel abutting relation, and sheet piling sections secured to the vertical edges of said panels.

In testimony whereof I affix my signature.

ALFRED H. GRUPPE.
